UNITED STATES PATENT OFFICE.

PERIES LINCOLN, OF COLDWATER, MICHIGAN.

KNIFE OR TOOL HANDLE.

SPECIFICATION forming part of Letters Patent No. 286,209, dated October 9, 1883.

Application filed December 18, 1882. (No model.)

To all whom it may concern:

Be it known that I, PERIES LINCOLN, a citizen of the United States, residing at Coldwater, in the county of Branch and State of Michigan, have invented certain new and useful Improvements in Knife or Tool Handles; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in knife or tool handles, whereby the knife-blade or button-hook, screw-driver blade, corkscrew, or other similar tools may be held securely inside the handle, extended outward for use, or 20 removed and replaced at will.

The object of my invention is to construct a cheap and durable handle that will admit of the knife-blade or other tool being entirely secured within the handle, forced outward, 25 and held in place for use at will, or be removed and another tool placed in position without weakening or deranging the handle. I attain these objects by means of the following construction, which will be more fully 30 pointed out in the specification and claims.

Figure 1 is a longitudinal sectional view of my device, showing a knife-blade extending from the handle, and by dotted lines the extended clamping-arm. Fig. 2 is a longitudinal 35 sectional view, showing the knife-blade secured inside the handle. Fig. 3 is a longitudinal sectional view showing a button-hook extending from the rear end of the handle. Fig. 4 is a perspective view showing screw-driver 40 blade extending; and Fig. 5 is a longitudinal view, showing knife-blade and screw-driver held in place.

Similar letters refer to similar parts throughout the drawings.

45 A represents a handle formed with open ends for the ingress and egress of tools, such as knife-blades, button-hooks, screw-drivers, &c. The space between the metal plates on the inside of the handle extends outward at each 50 end, terminating in open slots *a a'* at each extremity of said handle. One side of this

space is closed by a metal strip, *b*, that forms a back for the knife-handle. The opposite side of this space is covered by a pivoted arm, *B*, when the tool is inside the handle or when 55 the tool is extended for use. Arm *B* is formed with its outer edge flat and nearly straight from its outer end to near its inner end, and of sufficient width to rest on the edges of the metal plates forming the inside of the handle. 60 The outer end of arm *B* is recessed back to a square shoulder, *b*. An inclined flange or projection-rib, *c*, extends rearward from shoulder *b* to near the inner end of the handle. A pivot, *d*, passes through the upper edge of the 65 handle, near its inner end. Arm *B* is perforated at its inner end, through which pivot-pin *d* passes. Near the pivot-pin *d* an angular recess, *e*, is formed in the flange or projection *c*. The rear portion of arm *B* is curved 70 downward, with tapering sides to fit loosely between the sides of the handle.

The tools adapted to be used with handle *A* are formed with a projecting stud, *f*, on one edge of their rear portion, that is formed to engage with recess *b'* at the outer end of arm *B*, or with recess *e* on the inner end of the same, and where one tool is retained inside the handle and another thrust outward from the end for use, the inner curved end of the lever-arm 80 *B* engages with a square-shouldered recess, *g*, in the inner end of said tool. This curved recess is cut into the inner end of the tool and outward to near its outer edge, leaving a square-shouldered inward projection, *g'*, 85 formed to receive and hold the shouldered projection *h* on the inner end of the lever-arm *B*.

Having thus described my invention, what I desire to secure by Letters Patent is—

1. A knife or tool handle having an open 90 end, through which tools are extended, and an open side adapted to be closed by a lever pivoted at its inner end between the walls and near the inner end of said openings, the outer end of said lever abutting against a projection 95 on the inner edge of the tool, and thereby holding the same in place, substantially as shown and specified.

2. A knife or tool handle having open ends and an open side, through which tools are inserted and removed, and a longitudinally-tilting 100 lever-arm, at the inner end of which is

formed a recess to receive a corresponding projection formed upon a tool fitted in said handle, thus binding said tool in place, substantially as shown and specified.

5. 3. The lever-arm B, having an inclined projecting rib, c, said rib formed to pass between the sides of a tool-handle, at the inner end of which rib is formed a notch or recess to receive a corresponding projection formed upon a tool fitted into said handle, with angular notch or recess at the inner end of said arm, and a perforation in rear of said recess to receive a pivot-pin, substantially as shown.

4. A tool-handle formed as described, having a tool secured between the sides of the same by means of a pivoted lever, and a second tool extended from the inner end of said handle and held in place by the inner end of the same lever-arm, substantially as set forth.

In testimony whereof I affix my signature in presence of two witnesses.

PERIES LINCOLN.
